corporation of New Jersey

Application August 11, 1949, Serial No. 109,736

15 Claims. (CL 158—27.4)

1

This invention relates to hand torches for the cutting and scarfing of metals.

In torches of this type one of the most important features of construction and operation is the valve that controls the cutting or scarfing oxygen, because this valve is in almost continuous use by the operator. The construction and operation of this valve in prior torches have not always been wholly satisfactory for several reasons. One of the reasons is that it has been extremely difficult or even impossible to obtain refined control of the oxygen flow. A sudden surge of oxygen frequently occurs when the valve is first opened even a minute amount. Although, thereafter, the flow increases at a substantially constant rate as the valve is opened further, slight movements of the valve operating lever sometimes result in large flow variations. Due primarily to the first sudden surge of oxygen it is difficult to control a cutting or scarfing operation as carefully as is desired.

Another reason why prior hand cutting and scarfing torches have not been entirely satisfactory is that over a period of time their operation becomes fatiguing to the operator. Most torch operators acquire their own personal preferences as to the manner of holding and operating the torch, some preferring that the operating lever for the oxygen valve, which is usually mounted on the torch handle, be situated on the lower side of the torch, while others prefer that it be located on the top of the torch. The construction of prior torches does not permit the position of the valve-operating lever to be changed as desired by the operator, because the lever and the linkage from it to the valve are arranged in a fixed relation to the valve itself in such a manner that a change in position of the lever is impossible.

According to this invention, the torch valve that controls the cutting or scarfing oxygen is so designed that the flow of oxygen may be very finely regulated in such a way that all tendency toward sudden surging of the gas is obviated. The invention also contemplates the provision of means, including a valve-operating lever, for operating this valve which permits reversible and interchangeable positioning of the operating lever either at the top or bottom of the torch, depending upon the desire of the operator.

Moreover the valve not only provides a fine control of the flow of oxygen but it is extremely simple in construction. A short cylindrical rod having a tapered end, hereinafter called the valve member, constitutes the movable member of the valve and takes the place of the usual valve ele-

2

ment and valve stem. The valve member is slideable in a cylindrical bore in the valve block of the torch, the bore having a conical end constituting a valve seat with which the tapered end of the valve member cooperates. An inlet gas passage communicates with the cylindrical bore at the apex of its conical end and an outlet passage leads from the cylindrical portion of the bore. The tapered end of the valve member is provided with an O-ring which acts as a seal when the valve member is seated, and the cylindrical body portion of the valve member is provided with an O-ring which acts as a seal to prevent the gas from escaping around the valve member beyond the outlet gas passage. The pressure of the incoming gas acting on the valve member at its tapered end tends to move the valve member longitudinally and unseat it, but it is normally retained seated by mechanical pressure exerted on its rear end by operating mechanism which may be manually actuated to release the mechanical pressure and thereby permit the valve member to open.

The operating mechanism for the valve member comprises a hand actuated lever and operating connections between it and the valve member and including a part which contacts with the rear end of the valve member. A spring in the operating connections normally retains all parts of the valve-operating mechanism in a position such that said part which contacts with the rear end of the valve member exerts the above-mentioned mechanical pressure on the valve member to retain it seated, but when the hand actuated lever is depressed this part is retracted, thereby permitting the gas pressure acting on the valve member to move it longitudinally and open the valve. The hand actuated lever and the operating connections between it and the valve member are pivotally mounted on two pins carried by the valve block and located symmetrically at opposite sides of the valve member. The pins are removable so that the hand actuated lever and the operating connections can be removed and their position on the pins interchanged whereby the hand lever may be shifted from a position below the torch handle to a position above it or vice versa.

A hand cutting torch having a cutting oxygen valve and reversible valve-operating mechanism of the kind contemplated by the invention is illustrated in the accompanying drawings, in which:

Fig. 1 is a side elevation of the torch,

Fig. 2 is a partial sectional view of the torch

showing the construction of the cutting oxygen valve and its operating mechanism.

Fig. 3 is a view similar to Fig. 2 showing the operating mechanism moved to a position which permits opening of the valve.

Fig. 4 is a partial sectional view of the torch showing the operating mechanism for the valve in reversed position, and

Fig. 5 is a transverse section taken along line 5-5 of Fig. 2, some portions of the operating mechanism being removed.

Referring to the drawings and particularly to Fig. 1, a cutting torch 10 is provided with a head 11 in which is mounted the usual tip 12. A valve block 13 is located at the rear end of the torch 15 and is provided with fittings 14 and 15 to which suitable conduits are attached for feeding oxygen, and a fuel gas such as acetylene, to the valve block. A throttling valve 16 in valve block 13 controls the flow of acetylene which passes from the valve block through suitable conduits within a tubular handle portion 17 to a forward valve block 18, and thence to one of the connecting tubes 19, by which it is carried to the torch head 11. Oxygen is carried from valve block 13 forwardly through suitable conduits located within handle portion 17 to the valve block 18 where it is apportioned between the cutting oxygen stream and the preheating oxygen stream, the preheating oxygen then passing through one of the connecting tubes 19 to the torch head 11 where it is mixed with the acetylene to form a combustible gas mixture for the preheating flames. The flow of preheating oxygen is controlled by a valve 20 in the block 18. The flow of cutting oxygen is controlled by a hand actuated lever 21.

The cutting oxygen valve and its operating mechanism are shown most clearly in the cut-away views of Figs. 2-4. The valve consists of a valve block 22 and a cylindrical rod 23 constituting a piston-like valve member. The rear part of the valve block is bifurcated thus forming two rearwardly projecting spaced portions 22a and 22b (Fig. 5). The valve block also has a central bore 24 constituting a cylindrical valve member. The forward end of the valve chamber is provided with a conical portion 24' (Fig. 3) forming a valve seat. An inlet gas passage 25 communicates with the valve chamber at the apex of the conical portion 24' of the chamber. The valve member 23 has a tapered forward end 26 which is adapted to seat on the conical seat portion 24' of the valve chamber. An O-ring 27 of rubber or other suitable material is carried in an annular groove in the tapered forward end of the valve member and serves as a seal when the valve member is seated. A second O-ring 28 is located in an annular groove in the cylindrical body portion of the valve member to the rearward of its tapered forward end. An outlet passage 30 leads from the valve chamber 24 at a point along its cylindrical wall between its conical forward end and that portion of its wall contacted by the O-ring 28. The pressure of the incoming gas acts against the valve member 24 to open the valve, and when the valve is opened, the annular O-ring 28 prevents the escape of gas rearwardly past it and thus the gas may only leave the valve chamber by outlet passage 30. In order to close the valve, however, a positive force must be applied to the rear end of the valve member and this force is applied thereto by the spring means and valve-operating mechanism which will be subsequently described. Oxygen released by the valve passes through the

discharge or outlet passage 30 which delivers it to one of the connecting tubes 19 and thence to the head 11 and tip 12.

The operating mechanism for the valve includes a bell-crank lever 32 pivotally supported on a pin 33 (Figs. 2 and 3) extending between the spaced portions 22a and 22b of the bifurcated rear end of the valve block. One end of hand lever 21 is pivotally supported by a similarly mounted pin 34 (Figs. 3 and 4), the pins 33 and 34 being mounted in the valve block symmetrically with respect to the valve member above and below it. One arm 35 of the bell-crank lever extends across the rear end of the valve member 23 and is adapted to contact it and to force it forwardly into the valve chamber 24 so that its tapered forward end seats upon the seat portion 24' of the valve chamber when the bell-crank lever is turned clockwise (as viewed in Figs. 3 and 4) on its supporting pin. When turned on its supporting pin in the opposite direction, the bell-crank lever permits the valve member to be moved outwardly in the valve chamber by the pressure of the oxygen supply, thereby opening the valve and allowing the passage of oxygen through it.

A connecting link 37, angular in shape, is pivotally connected to the distal end of the second arm 38 of the bell-crank lever by a pin 39, and to the hand lever 21 by means of pin 40. Operation of the hand lever 21 imparts movement to the bell-crank lever through this connecting link. A coil spring 42 is mounted between the arm 35 of the bell-crank lever and the connecting link 37, one end being seated in a recess 43 in the arm of the bell-crank lever, and the other end in a recess 44 in the connecting link. A screw 45 has one end threaded into arm 35 of the bell-crank lever and extends through the coil spring and through an enlarged opening 46 in the connecting link. The screw 45 provides additional support for the spring 42 and has a head 47 which is larger than the enlarged opening 46 in the connecting link for a purpose which will be subsequently explained.

As shown in Fig. 5, each of the supporting pins 33 and 34 is mounted in two aligned openings in the spaced portions of the bifurcated rear end of the valve block 22, one of the openings being threaded to receive a threaded portion 48 at the end of the pin. Thus the pins can be positioned and removed like screws, openings 49 and 50 being provided in the handle portion 17 of the torch through which they can be positioned in and removed from the valve block. Because these supporting pins are symmetrically located with respect to the valve member 23, the operating mechanism for the valve may be reversed to position the hand lever 21 at the top of the torch handle, as shown in dotted lines in Figs. 1 and 4. To accomplish this reversal, pins 33 and 34 are first removed and then the valve-operating mechanism is removed through a slot 51 in the torch handle 17, which is provided to accommodate hand lever 21. The valve-operating mechanism, including hand lever 21, bell-crank lever 32, connecting link 37 and spring 42, is held together when removed by reason of screw 45 the head 47 of which will not pass through enlarged opening 46 of link 37. The handle casing 17, which is rotatable on the front and rear valve blocks when the supporting pins and valve-operating mechanism are removed, is then rotated so that slot 51 is located at the top of the torch. In this position the openings 49 and 50 in the

torch handle 17 will be displaced 180° and the opening 49 which originally registered with the upper pin 33 will now register with the lower pin 34, and the opening 50 will now register with the upper pin instead of the lower pin. It should here be noted that the pins are screwed into the valve block from opposite directions so that one of the two openings 49 and 50 will always lie adjacent the slotted end of one of the pins. The valve-operating mechanism is then inserted through slot 51 and the pins 33 and 34 are screwed back in place. The valve-operating mechanism will then be in the reverse position shown in Fig. 4, the hand lever 21 being thus located above rather than below the torch handle.

In operation, the hand lever 21 is depressed, i. e., moved inwardly into the torch handle, as shown in Figs. 3 and 4, against the force of the coil spring 42 and this turns the bell-crank on its pivot pin so that the valve member is permitted to move outwardly in the valve chamber under the pressure of the incoming gas, the gas being permitted to pass through the chamber and to the torch head and tip through discharge passage 30 and one of conduits 19. When the hand lever is released, the coil spring returns it to its normal position shown in Fig. 2 and the bell-crank lever is turned on its pivot pin to move the valve member forwardly into the valve chamber to seat its tapered end upon the conical seat portion of the valve chamber and to thereby prevent further flow of gas therethrough.

The arrangement and construction of the above-described valve and operating mechanism provides improved throttling and flow metering qualities. The cooperating conical surfaces of the valve are such that greater axial movement of the piston-like valve member is necessary to obtain a valve opening equivalent to that of a flat-seat type valve. Since a greater axial movement of the valve member is required to obtain a full opening of the valve, the flow may be varied with more control over the range from zero to full flow capacity. Also, the present valve may be opened without a sudden surge of gas such as occurs with certain commonly used valves which close in the direction of the gas flow and which are biased closed by a spring acting in the same direction. When that type of valve is "cracked," sudden equalization of the gas pressure at opposite sides of the valve element causes the valve to open more quickly. A surge of gas is thus released. In the present valve, even when the valve is opened, the balance of pressure across the valve member remains substantially constant because of the shape of the valve stem and the part which serves as the valve proper and because the valve opens in the direction of the gas flow through the valve.

The reversibility of the valve-operating mechanism makes the use of the torch less fatiguing to the operator when performing a succession of cutting or scarfing operations since it permits him to change the location of the hand lever 21 at the end of an operation, if he so desires, before starting the next operation.

While the invention has been specifically described in its application to a cutting torch, the principles of the invention are also applicable to scarfing torches.

I claim:

1. A hand torch having a handle portion, a valve block having a valve chamber provided with a valve seat, a valve member movable in said chamber and having a portion cooperating

with said seat, means for operating said valve member comprising a hand lever and linkage between the hand lever and the valve member, a pair of pins carried by the torch on one of which said hand lever is pivotally mounted and on the other of which said linkage is pivotally mounted, said pins being symmetrically located above and below the valve member and being removable to permit removal of the hand lever and the linkage from the torch and their remounting on the pins in reverse locations whereby the hand lever may be located either at the top or bottom of the handle portion of the torch.

2. A hand torch having a handle portion, a valve block having a valve chamber provided with a valve seat, a valve member freely movable in said chamber and having a portion cooperating with said seat, means for operating said valve member comprising a hand lever and linkage between the hand lever and the valve member, a pair of pins carried by the torch on one of which said hand lever is pivotally mounted and on the other of which said linkage is pivotally mounted, said pins being symmetrically located above and below the valve member and being removable to permit removal of the hand lever and the linkage from the torch and their remounting on the pins in reverse locations whereby the hand lever may be located either at the top or bottom of the handle portion of the torch.

3. A hand torch having a handle portion, a valve block having a valve chamber provided with a valve seat, a valve member freely movable in said chamber and having a portion cooperating with said seat, means for operating said valve member comprising a pair of supporting pins carried by the torch and symmetrically located with respect to the valve member and adjacent the rear end thereof, a hand lever pivotally mounted on one pin, a bell-crank lever pivotally mounted on the other pin and having a valve contacting arm extending across the rear end of the valve member, a link connecting the distal end of the other arm of the bell-crank lever to the hand lever whereby movement of said hand lever from a normal position turns the bell-crank lever about the axis of its pin in a direction to move the valve-contacting arm of the bell-crank lever rearwardly so that the valve member may be moved by gas pressure rearwardly in the valve chamber away from the valve seat, and a spring biasing the hand lever to its normal position and the bell-crank lever to the position in which its valve-contacting arm maintains the valve member seated.

4. A hand torch as set forth in claim 3 in which the hand lever is pivotally mounted on its pin at one end of the lever and the link connecting the bell-crank lever to the hand lever is connected to the hand lever intermediate the ends of the hand lever.

5. A hand torch as set forth in claim 3 having a tubular handle portion a part of which substantially encloses the valve member and the linkage between it and the hand lever, the tubular handle portion having a longitudinal slot in it through which the hand lever may extend.

6. A hand torch as set forth in claim 3 having a screw mounted in said valve-contacting arm

of the bell-crank lever, said connecting link having an enlarged opening through which said screw extends, and said spring being a coil spring mounted on the screw and compressed between said valve-contacting arm and said connecting link.

7. A hand torch as set forth in claim 6 in which said screw has a head at its distal end larger than the enlarged opening in the connecting link whereby passage of the screw entirely through the opening is prevented.

8. A hand torch having a valve block provided with a cylindrical valve chamber extending lengthwise of the torch the forward end of which is conical in shape and constitutes a valve seat and the rear end of which is open, a gas passageway communicating with the cylindrical valve chamber at the apex of its conical end, a second gas passageway communicating with said valve chamber at a point along its cylindrical wall, a cylindrical valve member freely movable in said valve chamber, said valve member having a tapered end adapted to seat on said conical seat portion at the forward end of the valve chamber when the valve member is urged into the valve chamber, a groove formed in the tapered end of the valve member, an O-ring mounted in said groove, an annular groove formed in the cylindrical portion of the valve member, an O-ring mounted in said annular groove, said annular groove and said last-mentioned O-ring being located on the valve member at such a position that the O-ring always engages the cylindrical wall of the valve chamber closer to the rear open end of the valve chamber than the point at which said second passageway communicates with it, a pair of supporting pins carried by the torch and symmetrically located with respect to the valve member and adjacent the rear end thereof, a hand lever pivotally mounted on one pin, a bell-crank lever pivotally mounted on the other pin and having a valve contacting arm extending across the rear end of the valve member, a link connecting the distal end of the other arm of the bell-crank lever to the hand lever whereby movement of said hand lever from a normal position turns the bell-crank lever about the axis of its supporting pin in a direction to move the valve-contacting arm of the bell-crank lever rearwardly so that the valve member may be moved by gas pressure rearwardly in the valve chamber thereby allowing passage of gas from one gas passageway to the other, and a spring biasing the hand lever to its normal position and the bell-crank lever to the position in which its valve-contacting arm maintains the valve member in the valve chamber with its tapered face seated on the seat portion of the chamber.

9. A hand torch as set forth in claim 8 in which said spring is mounted between and bears against the connecting link and the valve-contacting arm of the bell-crank lever.

10. A hand torch having a valve block provided with a cylindrical valve chamber at the forward end of which is a conical valve seat, the rear end of the valve block being bifurcated, a substantially cylindrical valve member freely movable in said valve chamber and having a tapered forward end adapted to cooperate with the valve seat of the valve chamber, the rear end of the valve member extending between the two portions of the bifurcated end of the valve block, a pair of supporting pins mounted in the two portions of the bifurcated end of the valve block and extending across the space therebetween, said pins being located symmetrically with respect to the

valve member, a hand lever having one end pivotally mounted on one of the supporting pins and extending into the space between the two portions of the bifurcated end of the valve block, a bell-crank lever pivotally mounted on the other pin and extending partially within the space between said two portions of the bifurcated end of the valve block, one arm of the bell-crank lever being a valve-contacting arm extending across the rear end of the valve member, a link connecting the distal end of the other arm of the bell-crank lever to the hand lever whereby movement of the hand lever from a normal position turns the bell-crank lever about the axis of its supporting pin in a direction to move the valve-contacting arm of the bell-crank lever rearwardly so that the valve member may be moved by gas pressure rearwardly in the valve chamber away from the valve seat, and a spring biasing the hand lever to its normal position and the bell-crank lever to the position in which its valve-contacting arm maintains the valve member seated.

11. A hand torch having a valve block provided with a bore extending into one end thereof forming a cylindrical valve chamber, said valve chamber having a conical end forming a valve seat within the valve block, the valve block being provided with an inlet gas passage communicating with the valve chamber at the apex of its conical end and also having an outlet gas passage communicating with the cylindrical portion of the valve chamber, a cylindrical rod-like valve member movable longitudinally in the valve chamber and having a tapered end adapted to cooperate with said conical valve seat, an annular groove formed in the tapered end of the valve member, an O-ring mounted in said last-mentioned annular groove, an annular groove formed in the cylindrical portion of the valve member, an O-ring mounted in said last-mentioned annular groove and O-ring being located on the valve member at such a position that the O-ring always engages the cylindrical wall of the valve chamber closer to the open end of the valve chamber than the point at which said outlet gas passage communicates with it, the pressure of the gas admitted through said inlet passage tending to move the valve member in the valve chamber to unseat the valve, and spring means biasing the valve member to seated position.

12. A hand torch having a valve block provided with a bore extending into one end thereof forming a cylindrical valve chamber, said valve chamber having a conical end forming a valve seat within the valve block, the valve block being provided with an inlet gas passage communicating with the valve chamber at the apex of its conical end and also having an outlet gas passage communicating with the cylindrical portion of the valve chamber, a cylindrical rod-like valve member movable longitudinally in the valve chamber and having a tapered end adapted to cooperate with said conical valve seat and projecting at its opposite end out of the valve chamber, an annular groove formed in the tapered end of the valve member, an O-ring mounted in said annular groove, an annular groove formed in the cylindrical portion of the valve member, an O-ring mounted in said last-mentioned annular groove, said last-mentioned annular groove and O-ring being located on the valve member at such a position that the O-ring always engages the cylindrical wall of the valve chamber closer to the open end of the valve chamber than the point at which said outlet gas passage communicates with

it, the pressure of the gas admitted through said inlet passage tending to move the valve member in the valve chamber to unseat the valve, and spring means acting on the projecting end of the valve member and biasing the valve member to seated position.

13. A hand torch having a handle portion, a valve block having a valve chamber provided with a valve seat, a valve member movable in said chamber and having a portion cooperating with said seat, means for operating said valve member comprising a hand lever and a linkage means between the hand lever and the valve member, a mounting for pivotally supporting said hand lever, and a mounting for pivotally supporting said linkage means, said hand lever and said linkage means being interchangeably mountable on said mountings, said linkage means when mounted on either mounting extending from the hand lever to the valve member, and said hand lever and said linkage means being operable in either interchangeable position on said mountings to operate said valve member, whereby the torch may be arranged for operation of the valve member by said hand lever and linkage means in either of two positions at the election of the operator.

14. A hand torch as set forth in claim 13 in which said handle portion comprises a tubular member rotatably mounted on the torch and having a slot therein for reception of the hand lever and through which said linkage means may be removed from the torch when it is desired to change the location of the hand lever.

15. A hand torch having a handle portion, a valve block having a valve chamber provided with a valve seat, a valve member movable in said

10

chamber and having a portion cooperating with said seat, and means for operating said valve member comprising a hand lever and linkage between the hand lever and the valve member, said hand lever and linkage being mounted on the torch adjacent the handle portion of the torch, and said linkage comprising a member having a valve-contacting portion, a connecting link connecting said member to said handle lever, spring means mounted between and bearing against said valve contacting portion of said member and said connecting link, and a screw mounted in said valve contacting portion of said member, said connecting link having an enlarged opening through which said screw extends and said screw having a head larger than said enlarged opening to prevent passage of the free end of the screw through said opening.
